UNITED STATES PATENT OFFICE.

CHARLES SPIRO, OF NEW YORK, N. Y.

SILENT TYPE-BAR ACTION.

Application filed May 29, 1926. Serial No. 112,557.

This invention relates to a typebar action and particularly to a construction adapted to reduce to a minimum the noise incident to the printing contact of a pivoted typebar in a front strike type of machine, and the consequent wear and injury to the parts resulting from such violent impact.

In this art every effort is now being made to render the typebar action practically noiseless or silent, and various means have been used for this purpose, such as toggle actuating connections which reduce the typebar speed as it approaches the printing point. Such a connection involves the use of numerous joints and requires a material pressure on the key in initiating the typebar movement.

It has been found particularly desirable to provide for a silent action of the usual pivoted front strike typebar actuated by a lever with a pin and slot connection to the typebar. In prior constructions of such a connection the relation of the pin of the actuating lever to the typebar slot is such that the lever continues its pressure upon the typebar even after it has reached the printing limit of its travel which results in a very noisy impact with the platen, or with an abutment member if used.

To obviate such objections and effect the improved results desired, I have provided an actuating lever having its pin, operating in the typebar slot, so disposed as to traverse an arc tangential to the longitudinal axis of the typebar slot at the printing limit of its movement, whereby no pressure can be transmitted to the typebar after its printing impact with the platen. For this purpose the radius of the actuating lever is shorter than usual so that the curve of acceleration is greater, and after the peak is reached the decrease in speed is greater, and thus assists in the silencing action. A similar relation of parts is maintained at the opposite or rest position of the typebar which is thereby supported by the lever and avoids the necessity of the separate rest or support. In such a connection between the typebar and actuating lever, the greatest leverage is secured in starting the movement causing an easy initial depression of the keylever, and the leverage decreases and the speed increases as the lever pin approaches the axis of the typebar. After passing the mid-stroke position the leverage increases with consequent decrease of speed until the parts reach a po-

sition at the end of the stroke where a plane through the pivot and pin of the actuating lever lies at substantially a right angle to the longitudinal axis of the typebar slot and no further movement can be transmitted to the typebar. This positively controls the typebar travel independently of the pressure applied upon the keylever as at the end of its travel the actuating lever not only ceases to impel the typebar but holds it against further forward or rebound motion.

It is also important in the assemblage of this invention to provide actuating levers on which the typebar connections are equally spaced from the lever pivots in order to effect an even leverage at all points in the arc of the typebar sector. This involves the use of sub-levers connected to the key levers and having vertical arms at successively different elevations from which connecting ligaments extend to the actuating levers in a plurality of horizontal planes.

The invention has for an object to provide a novel and improved construction wherein the connection between the actuating lever and typebar is so disposed that no pressure is transmitted from one to the other as the typebar reaches the printing point.

Another object of the invention is to present a new typebar action including a pivoted typebar and an actuating lever therefor having a pin and slot connection in which the arc of travel of the pin is disposed tangential to the longitudinal axis of the slot of the typebar when the typebar is in printing position, whereby the bar is brought to rest and there held against movement relative to its actuating lever.

A further object of the invention is to provide a typebar action including a slotted typebar and actuating lever having a connecting member disposed so that a plane extending through said member and the pivot of the lever will lie at a right angle to the longitudinal axis of the slot of the typebar as the bar approaches either limit of its travel, which prevents the application of further power to the typebar and retains the same in either its position of rest or printing position.

The invention also presents a novel combination wherein the actuating levers cease to apply power to the typebars as they approach their printing position, each of said levers being of equal operative length and connected by horizontally disposed ligaments

with a series of sublevers of varying height adapted to be actuated by the key levers of the machine.

Other and further objects and advantages 5 of the invention will be hereinafter set forth and the novel features thereof defined by the appended claims.

In the drawing—

Figure 1 is a sectional elevation showing 10 the action applied;

Figures 2, 3 and 4 are details showing successive steps in the movement of the typebar.

Like numerals refer to like parts in the several figures of the drawing.

15 In the application of this invention I use instrumentalities common in the art, but so proportioned and arranged as to effect the novel function of relieving the typebar from pressure upon its printing engagement at the platen. A desirable form of the invention is herein disclosed and comprises the key lever 10 pivoted at 11 and normally elevated into engagement with a stop 12 by the spring 13. The downward travel of the lever may be 20 limited by the usual stop, while a vertical extension 15 from the lever carries a pin 16 disposed in the slotted arm 17 of the sublever 18. The series of these levers are pivoted in a single horizontal plane and the vertical arms thereof vary in length from this 25 pivot 19 for the sublevers so as to dispose the pivoted connecting ligaments 20 in a series of parallel horizontal planes. The ligaments are connected at substantially the midlength 30 of the actuating levers 21 which are of equal operative length to effect an even leverage upon each typebar 22. The levers 21 are pivoted at 23 upon a segment 28 arranged concentric to the segment 29 of the typebar 35 pivots 24, and the connecting pins 25 upon said levers are each disposed at an equal distance from the pivots 23 so that the pressure at the printing point of each typebar is relieved to insure silencing. This is 40 also facilitated by the sublevers of different heights and the connecting ligaments in parallel horizontal planes to avoid angle distortion and apply a direct motion to the 45 actuating lever.

50 The elements just described are duplicated for the several units of the action so that the operation of only one of the actuating levers will be described. This lever is provided with the connecting pin or similar member 25 operating in a slot 26 in the tail 55 27 of the typebar 22, and such pin is located at a distance from the pivot 23 of the actuating lever so that as it approaches either extreme of its movement its arc of travel is tangential to the length or longitudinal axis of the slot 26. The radius of the pin is therefore less than in the usual typebar action and the pin applies no pressure to the typebar at either end of the lever stroke 60 but acts to hold the typebar against any rela-

tive movement. This results in the engagement of the type with the paper upon the platen 30 with only sufficient force to produce the desired imprint and avoids a violent impact producing noise and injury to the type or platen at this point.

70 Referring to Figures 2, 3 and 4 it will be noted that the plane *c-c* through the pin and pivot of the actuating lever lies at substantially a right angle to the longitudinal axis *d-d* of the typebar slot at either limit of movement or position of rest, and if such lever be straight the length of the lever extends at the angle stated. This results in 75 reducing the usual distance of the pin from the pivot of the actuating lever so that it will travel in an arc *a-a* intersecting the arc *b-b* which is the path of the outer end of the typebar slot. These arcs join at the 80 opposite points of rest where the arc *a-a* lies tangential to the axis *d-d* and the arc *b-b* is tangential to plane *c-c* so there can be no further movement in the previous direction of travel, and the typebar is retained 85 or locked against any movement in either 90 direction relative to its actuating lever.

95 This construction provides for an easy starting of the stroke from the rest position of Figure 2 by applying the greatest leverage to the typebar at that period and gradually 100 reducing the leverage and increasing the speed until the pin of the actuating lever reaches its point of travel nearest the typebar pivot, as in Figure 3. From this point the speed decreases as the leverage increases to 105 apply more power until the position is reached at the end of the stroke where no pressure is applied to the typebar at the printing position of Figure 4. The result is 110 the practical elimination of the hammer blow and the impact of the type is only sufficient for the printing purpose. The pressure at this impact can be varied as found desirable for different classes of work by a proper relative adjustment of the pin and slot connection at the typebar. It will also be 115 obvious that such connection may be reversed, that is, the pin located upon the typebar instead of the lever, and that the contour of the cooperating slot may be varied. The actuating lever supports the typebar when at 120 rest without the use of the usual member upon the frame for that purpose, as with the parts in the dotted line position of Figure 1, the typebar is locked and supported 125 against downward movement by the pin of the actuating lever positioned relative to the slot of the typebar, as in Figure 2. This locking of the typebar against motion relative to its actuating lever prevents chattering or rebound from its position of rest which is liable to reduce the speed of operation through collision with an adjacent bar starting to move, or the holding of the carriage feed dogs from completing their opera- 130

tion for letter space travel. At each limit of travel the typebar is held against any movement, except by intentional actuation of the key lever, and this can only effect a travel in a direction reverse to its previous movement. This is incident to the relief of the typebar from the driving action of the actuating lever which at that instant retains the typebar against any relative movement.

10 It will be seen that the invention provides for a silent typebar action applicable to the usual front strike typebar and is therefore adapted to be embodied in most of the standard typewriter constructions. While the details of the invention have been specifically shown and described, the invention is not confined thereto, as changes and alterations may be made without departing from the spirit of the invention as recited in the following claims.

What I claim is:—

1. In a typebar action, a pivoted typebar, an actuating lever therefor having a pin and slot connection with the typebar in which the pin engages a wall of the slot to continuously apply power to the typebar up to the point of printing impact and thereafter remains inoperative upon said slot wall to further rotate the typebar, and a key lever operatively connected to said actuating lever.

2. In a typebar action, a pivoted typebar, an actuating lever therefor having a pin and slot connection with the typebar in which the pin engages a wall of the slot to continuously apply power to the typebar up to the point of printing impact and thereafter remains inoperative upon said slot wall to further rotate the typebar, said pin being disposed to engage a slot wall at the opposite extreme of travel of the typebar to support the same at its position of rest, and a key lever operatively connected to said actuating lever.

3. In a typebar action, a pivoted typebar, a pivoted actuating lever therefor having a pin and slot connection with the typebar in which the pin engages a wall of the slot to continuously apply power to the typebar up

to the point of printing impact and thereafter remains inoperative upon the slot wall 50 with the arc of travel of the pin tangential to the longitudinal axis of the slot, and an operative connection from the key lever to move the pin of the actuating lever in an arcuate path.

4. In a typebar action, a pivoted typebar having a slotted tail, a pivoted actuating lever having a pin traversing an arcuate path within the slot of said tail to continuously apply power to the typebar up to the point of 60 printing impact and thereafter remain inoperative upon the slot wall to further rotate the typebar, the longitudinal axis of the lever being then at a right angle to the longitudinal axis of the slot, and a key lever 65 operatively connected to said actuating lever.

5. In a typebar action, a slotted typebar, an actuating lever having a pin disposed in said slot to traverse an arc opposite to the 70 arcuate path of the outer end of the slot, said arcs intersecting when the typebar is at the printing impact position to prevent further application of power from the pin to the slot wall and also intersecting when the 75 typebar is at its opposite rest position, and a key lever operatively connected to move the pin of the actuating lever in an arcuate path.

6. In a typebar action, a series of typebars pivoted upon a segment, a series of actuating levers pivoted upon the segment concentric to the typebars and having pin and slot connections therewith disposed at equal distances from the lever pivots with the pins positioned to continuously apply power to 85 the typebar up to the point of printing impact and thereafter remain inoperative upon the slot wall to further rotate the typebar, sub-levers pivoted in a horizontal plane and having vertical arms of different heights, 90 ligaments connecting said arms and actuating levers, and key levers operatively connected to said sub-levers.

In testimony whereof I affix my signature.

CHARLES SPIRO.
